[57] CLAIM

The ornamental design for a lavatory, as shown and described.

DESCRIPTION

FIG. 1 is a perspective view taken from the top, front and left side of a lavatory showing my new design; FIG. 2 is a top plan view thereof;

FIG. 3 is a cross-sectional view taken on line 3—3 of FIG. 2; and,

FIG. 4 is a cross-sectional view taken on line 4—4 of FIG. 2.

The fragmental broken line representation of a counter top in FIG. 1 is for the purpose of illustration only and forms no part of the claimed design.

FIG. 1

FIG. 2

FIG. 3

FIG. 4
